UNITED STATES PATENT OFFICE.

GEORGE R. UNKEFER, OF CHICAGO, ILLINOIS.

RECEPTACLE.

1,291,279.

Specification of Letters Patent.

Patented Jan. 14, 1919.

Application filed February 19, 1917. Serial No. 149,438.

To all whom it may concern:

Be it known that I, GEORGE R. UNKEFER, citizen of the United States, residing at Chicago, in the county of Cook and State of Illinois, have invented a certain new and useful Improvement in Receptacles, of which the following is a full, clear, concise, and exact description.

My invention relates to receptacles that are provided with discharge spouts, receptacles of this kind being used, for example, in packaging paint, varnish, molasses, etc. I provide the spout of such a receptacle with a cap, and the receptacle itself I provide with 10 flexible tongues whose tips may be bent into engagement with said cap. The closure cap is provided with a bead that is engaged by the tips of the tongues to hold the cap in place. The inner surface of the top wall of 20 the cap has a facing of some suitable material that will hermetically seal the discharge end of the spout, a suitable material being a disk of paper suitably treated with oil and which may be merely inserted between the 25 discharge end of the spout and the inner surface of the top wall of the closure cap.

I will explain my invention more fully with reference to the accompanying drawing showing the preferred embodiment thereof 30 and in which Figure 1 is a sectional view on line 1—1 of Fig. 2; Fig. 2 is a plan view; and Fig. 3 illustrates component parts of the structure in separated relation.

Like parts are indicated by similar characters of reference throughout the different figures.

The receptacle illustrated is of sheet metal, the top side 1 of the receptacle being provided with the spout 2. This spout is 40 formed separately from the receptacle, that is made with an outwardly projecting circular lip 3 that surrounds the circular discharge opening in the receptacle and is itself surrounded by the circular base of the 45 spout. Said lip and spout are fastened together as by soldering.

The circular base of the spout carries upwardly extending tongues 4 arranged on a circle for firmly binding the closure cap 5 in 50 place. This closure cap is provided with a skirt 6 which carries a circular bead 7 which surrounds the skirt and which may be integrally formed with the cap by outwardly curling the edge portion of the cap skirt. This circular bead is of a diameter which is less than 55 the diameter of the circle circumscribed by

the tongue whereby the cap may be brought to position without turning it. This is the bead is insertible between the tongues consequent upon mere longitudinal movement 60 of the cap, the diameter of the circle circumscribed by the bead being sufficiently small.

By means of a suitable tool, the upper ends of the flexible tongues may be bent or curled over the top of bead to draw the 65 closure cap down over the spout with sufficient pressure to hold the preferably imperforate disk 8 of oil paper or other suitable material in sealing engagement with the discharge end of the spout and the inner surface 70 of the top wall of the closure cap. The axial length of the closure cap is less than that of the spout, so that in curling the tips of the tongues against the top of the circular bead, the cap will be drawn down on 75 the spout firmly to press the sealing disk between the discharge end of the spout and the inner surface of the top wall of the cap. This disk or sealing element 8 may be un-assembled with the closure cap, being loosely 80 placed on the spout before the application of the cap.

Owing to the flexibility of the tongues, they may readily be uncurled or bent outward to permit of the removal of the cap for 85 the discharge of material from the receptacle, whereafter the cap and receptacle may again be held together by bending the tongues or locking elements 4 into holding engagement with the locking bead or ele- 90 ment 7.

The base of the closure cap may be curled outwardly and upwardly to form a gutter 9 that is positioned to catch material that flows downwardly upon the exterior of the spout. 95 The tongues 4 rise from and constitute continuations of the outer rim 10 which surrounds the base of the spout and forms there-with the gutter.

While I have herein shown and particularly described the preferred embodiment of my invention I do not wish to be limited to the precise details of construction shown, as changes may readily be made without departing from the spirit of my invention, but 105 having thus described my invention I claim as new and desire to secure by Letters Patent the following:

The combination with a receptacle having a discharge opening; of a spout having a 110 circular base secured to said receptacle in line with said discharge opening; a skirted

closure cap having a circular bead upon and surrounding the skirt of the cap; tongues carried at the circular base of the spout and inclosing a circle in which the circular bead is received; and a sealing disk interposed between and engaging the discharge end of the spout and the inner surface of the top wall of the closure cap, the tips of said tongues being adapted 10 to be bent into engagement with the top of said bead to lock the closure cap and spout together, the axial length of the closure cap

being less than that of the spout so that in curling the tips of the tongues against the top of the circular bead, the cap will be 15 drawn down on the spout firmly to press the sealing disk between the discharge end of the spout and the inner surface of the top wall of the cap.

In witness whereof I hereunto subscribe 20 my name this 16th day of February, A. D. 1917.

GEORGE R. UNKEFER.
